UNITED STATES PATENT OFFICE.

HUBERT LANG, OF CHICAGO, ILLINOIS, ASSIGNOR TO THE GOSS PRINTING PRESS COMPANY, OF CHICAGO, ILLINOIS, A CORPORATION OF ILLINOIS.

ROTARY FOLDING MECHANISM FOR PRINTING-PRESSES.

No. 899,742.

Specification of Letters Patent.

Patented Sept. 29, 1908.

Application filed April 13, 1908. Serial No. 426,808.

To all whom it may concern:

Be it known that I, HUBERT LANG, a citizen of the United States, residing at Chicago, in the county of Cook and State of Illinois, 5 have invented certain new and useful Improvements in Rotary Folding Mechanism for Printing-Presses, of which the following is a specification, reference being had to the accompanying drawings.

10 My invention relates to improvements in rotary folding mechanism for printing presses and particularly to improvements in the mechanism shown and described in Letters Patent of the United States, No. 871,038, to 15 Hans P. Husby, granted November 12, 1907, in which the folding blade in a rotary carrier is operated from normal position into operative position and out of operative position into normal position by a moving guide, 20 which, while traveling in the same direction with the folding blade, acts upon it to move it into and out of operative position; and its object is to provide new and improved mechanism by which the folding blade may be operated without any blow or violent contact 25 of parts, thereby increasing the speed at which the blade may be operated.

In the accompanying drawings:—Figure 1 is an end view with a portion of the frame- 30 work removed to show the parts. Fig. 2 is an end view, showing the carrier, folding blades, and operative parts in other positions. Fig. 3 is a side elevation. Fig. 4 is a detail, being a view of the gear and operating 35 guide thereon.

5 indicates a rotary carrier of the ordinary form and construction which is mounted on a shaft 6 journaled in a suitable framework, as 7. The rotary carrier is preferably constructed 40 to coöperate with the rotary cutting cylinder 8, and to that end is provided with grooves 9 which are designed to coöperate with the knife 10 on the cutting cylinder 8. The carrier 5 is also provided with the usual 45 impaling pins 11 which may be of any well-known form and construction and operate in any well-known manner and hence are only conventionally illustrated.

12—12 indicate folding rollers which are 50 mounted below the rotary carrier 5 in a suitable portion of the framework, as 7^a, and are operated in the well-known usual manner.

13—13 indicate shafts which are journaled 55 in suitable bearings, as 14, in the rotary carrier 5, and, in the construction shown, are

two in number diametrically opposite one another.

15 indicates folding blades which are secured to the shafts 13 in any well-known manner.

16 indicates tumbling-levers which are secured upon the ends of the shafts 13 outside of the rotary carrier 5 and are provided upon their ends with studs 17, preferably in the form of rollers, and projecting outwardly 65 from the surface of the tumbling-levers 16.

18 indicates a guide-ring open at the bottom above the folding rollers to permit the operation of the folding blade hereinafter described, upon the inner surface of which 70 the studs or rollers 17 on the tumbling-levers 16 bear to retain the blades in normal position while not operating,—that is to say, in the form in which my improvements are 75 illustrated, with the blade at right angles to the radius of the rotary carrier which passes through the center of the shaft 13.

19 indicates a gear which is secured to the shaft 6.

20 indicates a gear which is journaled upon 80 a stud 21 on the framework 7 and meshes with the gear 19. The gears 19—20 contain an equal number of teeth so that they rotate at the same speed.

22 indicates guides which are secured to 85 the inner surface of the gear 20 or formed integral therewith, the guides 22 having their interior surfaces parallel with one another so as to provide a groove 23 which, in the form shown, extends diametrically across the gear 90 20 open at both ends. The gear 20 is so located that its axis lies in the vertical plane which is tangent to both the folding rollers at their point of contact and is slightly above the axial lines of the folding rollers 12. The 95 diameters of the gears 19 and 20, and the length of the guides 22 are so proportioned to the distance of the center of the shaft 13 from the center of the shaft 6, and the gear with the guides 22 is so positioned that at 100 just the moment when the roller on the lead end of the tumbling-lever comes into position to register with the open end of the groove, as shown in Fig. 1 and as hereinafter described, the central line of the groove 23 105 will be tangent to the circle in which the axial line of the shaft 13 travels.

The operation of my device is as follows:—The paper, being engaged by the pins 11 on the rotary carrier, is carried around the car- 110

rier in the usual manner. At the instant that the groove 23 reaches the position shown on Fig. 1,—namely with the central line tangent to the circle in which the axial line of the shaft 13 travels,—the tumbling-lever has come into position to have the roller upon its lead end enter the groove. The parts revolving in the direction indicated by arrows in the several figures, the end of the 10 groove which engages the tumbling-lever will be traveling in the same direction at the moment of its engagement, and, as the radius of the curve in which the tumbling-lever travels is greater than the radius of the gears 19—20, 15 the lead end of the tumbling-lever, as the parts rotate, will be moved into the position shown in dotted lines in Fig. 2, tucking the paper, which in the meantime has been severed by the knife 10, between the folding 20 rollers by which the fold is completed in the usual manner. As the rotation continues, the engaged roller on what has so far been the lead end of the tumbling-lever will travel up the groove and the tumbling-lever will be 25 moved out of folding position. Just at the moment when the engaged roller is about to leave the groove, the central line of the groove will again be tangent to the circle in which the axis of the tumbling-lever travels and the 30 folding blade, moved out of folding position into normal position, will be delivered to the guide-ring to be carried around and again operated.

As the groove 23 extends diametrically 35 across the gear 20, in the form in which I have embodied my invention, and as the gear 20 makes one revolution for each revolution of the rotary carrier, the folding blade diametrically opposite the one which has 40 just been operated will come into position to be operated from the other end of the groove 23, and the tumbling-levers and folding blades diametrically opposite each other will be successively operated, one from one end 45 and the other from the other end of the groove. This is the form in which I prefer to embody my invention, but it is of course obvious that instead of the two tumbling-levers and the two folding blades the carrier 50 might contain only one or more than two tumbling-levers and folding blades, the parts being correspondingly proportioned and operated, without departing from the spirit of my invention. It is obvious also that the 55 direction of rotation might be opposite to that indicated, the cutting cylinder being suitably disposed, and the operation would be exactly the same.

Inasmuch as the engaging groove on the 60 gear or rotary member, at the moment of its engaging the lead end of the tumbling-lever, is tangent to the circle in which the axis of the tumbling lever moves, and as this engagement is effected while traveling in the 65 same general direction with the lead end of

the tumbling-lever, it is obvious that the tumbling-lever and therefore the folding blade will be moved from the normal position in the guide to folding position without shock or violent contact of parts, and as the 70 blade is moved out of folding position towards normal position while the parts are traveling in the same general direction, and at the moment of the release of the tumbling-lever from the guide the guide groove is again 75 tangent to the circle of travel of the axis of the tumbling lever, it is obvious that the blade will be moved out of folding position and delivered to the guide-ring in normal 80 position without a shock or violent contact of parts, enabling the device to be rotated at a high rate of speed.

What I claim as my invention and desire to secure by Letters Patent is:—

1. In combination, a rotary carrier, a folding blade carried thereby, a tumbling-lever on said folding blade, a guide-ring for said tumbling-lever, fold-laying devices, a rotary member, whose axis lies in the plane which is tangent to said fold-laying devices and passes through the axis of the folding cylinder and a single radial guide thereon adapted to receive said tumbling-lever from said guide-ring in normal position, and, by its rotation, to move said folding blade into and out of folding position and deliver said tumbling-lever to said guide-ring in normal position.

2. In combination, a rotary carrier, a folding blade carried thereby, a tumbling-lever on said folding blade, a guide-ring for said tumbling-lever, fold-laying devices, a rotary member, and a radial guide thereon adapted to receive said tumbling-lever from said guide-ring in normal position while substantially in line with said tumbling-lever, and, by its rotation, to move said folding blade into and out of folding position and deliver said tumbling-lever to said guide-ring in normal position when said radial guide and said tumbling-lever are substantially in line with each other.

3. In combination, a carrier, a folding blade, a tumbling-lever connected to said folding blade, engaging studs on said tumbling-lever, a guide-ring, folding rollers, a rotary member, and a radial guide thereon adapted to engage the stud on the lead end of said tumbling-lever when said tumbling-lever is in normal position and said guide is substantially in line therewith, and, by its rotation, to move said folding blade into and out of folding position and deliver said tumbling-lever to said guide-ring in normal position when said radial guide and said tumbling-lever are again substantially in line with each other.

4. The combination with a rotary carrier, a folding blade carried thereby, a tumbling-lever connected with said folding blade, a

guide-ring for said tumbling-lever, and folding rollers, of a rotary member, and a radial guide thereon adapted to engage said tumbling-lever when said radial guide is substantially tangent to the curve of travel of said folding blade, and, by its rotation, to move said folding blade from normal into folding position and from folding into normal position and deliver said tumbling-lever 10 to said guide-ring when said radial guide is substantially tangent to the curve of travel of said folding blade.

5. The combination with a carrier, a folding blade carried thereby, a tumbling-lever connected with said folding blade, a guide-ring for said tumbling-lever, and fold-laying devices, of a rotary member whose axis lies in the plane which is tangent to said fold-laying devices and passes through the axis 20 of the folding cylinder, a single radial groove on said rotary member adapted to receive the lead end of the tumbling-lever from said guide-ring with said tumbling-lever in normal position and to move said folding blade 25 into and out of folding position and to deliver said tumbling-lever to said guide-ring with said tumbling-lever in normal position.

6. The combination with a carrier, a folding blade carried thereby, a tumbling-lever connected with said folding blade, a guide-ring for said tumbling-lever, and fold-laying devices, of a rotary member provided with a radial groove adapted to receive the lead end of the tumbling-lever from said guide-ring 35 with said tumbling-lever in normal position and while said guide is substantially in line with said tumbling-lever and to move said folding blade into and out of folding position and to deliver said tumbling-lever to 40 said guide-ring with said tumbling-lever in normal position when said radial groove and said tumbling-lever are again substantially in line.

7. The combination with a carrier, a folding blade carried thereby, a tumbling-lever connected with said folding blade, a guide-ring for said tumbling-lever, and fold-laying devices, of a rotary member provided with a radial groove adapted to receive the lead 45 end of the tumbling-lever from said guide-ring while substantially in line with said tumbling-lever and with said tumbling-lever in normal position and to move said folding blade into and out of folding position and to release said tumbling-lever from 50

the same end of said groove by which it was first engaged and to deliver it in normal position to said guide-ring when said groove and said tumbling-lever are again substantially in line.

8. The combination with a carrier, diametrically-oppositely-disposed folding blades, a tumbling-lever connected with each of said folding blades, a guide-ring for said tumbling-levers, and fold-laying devices, of a 60 rotary member, and a diametrically-disposed guide on said rotary member adapted successively at its opposite ends to alternately engage said tumbling-levers in normal position and to move the respective folding 65 blades into and out of folding position and to release the tumbling-lever from the same end of said guide by which it was first engaged and deliver the same in normal position to said guide-ring.

9. The combination with a carrier, diametrically-oppositely-disposed folding blades, a tumbling-lever connected with each of said folding blades, a guide-ring for said tumbling-levers, and fold-laying devices, of a 70 rotary member, and a diametrically-disposed guide on said rotary member adapted successively at its opposite ends to alternately engage said tumbling-levers in their normal position when substantially in line therewith, 75 to move them into and out of folding position, and to deliver them in normal position to said guide-ring from the same end of said guide by which they were engaged.

10. The combination with a carrier, a pair 80 of tumbling-levers, oppositely-disposed folding blades, one of said tumbling-levers connected with each of said folding blades, a guide-ring for said tumbling-levers, and fold-laying devices, of a rotary member provided 85 with a groove extending diametrically across it and adapted successively at its opposite ends to alternately engage the lead ends of said tumbling-levers while the same are in normal position, and, by its rotation, to move 90 said folding blades into and out of folding position and deliver the said tumbling-levers in normal position to the guide-ring from the same end of said guide by which they were engaged.
